SWITCH

Application filed January 12, 1931. Serial No. 508,309.

This invention relates to electrical switches such as are used on high voltage transmission systems and, among other objects, aims to provide an improved, high-pressure contact 5 for air-brake switches of the jaw and blade or knife type. The main idea is to provide a strong, durable and relatively cheap switch having a great current carrying capacity and provided with means whereby the circuit may 10 be made and broken by a powerful lever action so that the blade is self-cleaned and will clear the contacting parts of considerable ice.

Other aims and advantages of the invention 15 will appear in the specification, when considered in connection with the accompanying drawing, wherein:

Fig. 1 is a fragmentary side elevation of a single switch embodying the invention; 20 Fig. 2 is a top plan view of the contact parts shown in Fig. 1; and

Fig. 3 is an end elevation.

Ordinary high tension switches usually have large spring jaws presenting flat contact surfaces for the flat ends of switch blades. In such switches, the spring pressure on the jaws is generally quite small so that the blades can easily be manipulated to make and break the circuit. The current 25 carrying capacity of low-pressure contacts is directly proportional to the contacting areas. Hence, the contact elements, including the blades and jaws, are necessarily large and expensive. High pressure, clean contacts 30 will carry heavy loads and their capacity is not dependent upon contact area but increases in proportion to the pressure within limits. This invention therefore provides an improved high pressure contact which enables 35 the parts to be made much smaller than the ordinary surface contact elements of the same current carrying capacity.

In this example, the illustrated improvements are applied to a horizontal air-break 40 switch, but it will be understood that the invention is equally applicable to vertical switches. In fact, either type of switch may be used interchangeably.

Referring particularly to the drawing, the 45 jaws are mounted on a bracket 10 which is

adapted to be secured on the top of an ordinary pin-type insulator (not shown). The bracket has an arm 11 to which a conductor is adapted to be secured in the usual manner. On the top of the bracket is secured a trans- 55 verse spring plate 12 which may be made of a rust-proof bronze having thin copper plates 13 applied to both sides to increase the conductivity. The thickness of the plate is determined by its length and the amount of 60 spring pressure to be exerted on the jaws. On the opposite end portions of the plate are secured jaw elements 14 and 15 so shaped as to provide the usual flared bight portion 65 between them to guide the switch blade. The jaw 14 has a horizontal contact arm 16 which is cut away slightly to afford blade clearance at the inner end of its contacting lower face and the jaw 15 has a rearwardly projecting 70 contact arm 17 opposite the arm 16 and terminating short of the vertical leg of the jaw 14. The end of the arm 17 is shown as having an integral vertical flange 18 to provide a combined stop and guide for the 75 switch blade. As shown in Figs. 1 and 2, the flange projects outwardly beyond the jaws so that its outer end will act as a fulcrum for releasing the blade as hereinafter described. The jaws are shown as having integral, rearwardly extending fingers or projections 19 and 20 extending beyond the end 80 of the flange 18 and having a transverse fulcrum pin 21 secured in openings in their outer ends. This pin serves as a fulcrum or abutment for the outer end of the blade to give it powerful leverage when it is being closed, as will be described. The projecting end of the flange 18 is integrally connected 85 to the finger 20 so that the finger acts as a reinforcing or strengthening flange. 90

The blade is of the toggle or jointed type, conveniently being made of a pair of spaced parallel copper bars 22 constituting one leg and a cast copper or bronze tip 23 constituting the other leg, the tip being pivoted between the bars on a bolt 24. A wire spring 25 having coils 26 on one end of the bolt is connected normally to break the knee joint so that the legs assume the relative angular 95 positions shown by the dotted lines in Fig. 2. 100

The pivoted end of the blade tip preferably has a stop lug 27 arranged to strike a stay pin 28 between the bars 22 and thus limit the relative swinging movement of the tip.

In Figs. 1 and 3 the blade tip is shown as having a thickened contact portion 29 which has its opposite faces rounded or curved so that it is more or less elliptical-shaped in cross section and will more easily enter the bight portion of the jaws. Moreover, this shape reduces the sliding friction between the blade and the faces of the jaws because it initially has line instead of surface contact with the jaw faces. Further, the concentrated rubbing action will clean the jaw faces and the blade and insure good metal to metal contact.

The blade tip is shown as having a reduced extension or lever arm 30 adapted to strike the vertical flange 18 as the blade closes so as to be guided behind the fulcrum pin 21 upon the initial closing movement due to the straightening of the knee joint. As the contact portion 29 enters the jaws and the lever arm strikes the flange 18, the knee joint begins to straighten and the lever arm 30 swings against the pin 21 about the jaws as a pivot. Further, closing movement of the blade forces it into the jaws by a lever action, the mechanical advantage of which is measured by the ratio between the distance from the fulcrum pin 21 to the knee joint or axis of the bolt 24 and the distance from the fulcrum pin to the middle of the jaw faces. In this instance, the ratio is about 3 to 1, but it may be varied according to the size of the switch and the pressure exerted by the jaws. Hence, the force necessary to be applied manually to close the blade need not be any greater than that exerted on the common type of switch.

As the blade closes and the knee joint straightens the contact portions 29 move about the pin 21 as a pivot and also move longitudinally outwardly. This compound movement enables the contact faces to wear themselves clean where they rub against the jaw faces.

When the blade is opened, the knee joint breaks first and the lever arm 30 swings into contact with the outer end of the flange 18 which then acts as a fulcrum. The mechanical advantage is now sufficiently great to move the blade very easily so that it will clear the jaws and itself of any ice that may be formed on them.

Since the high pressure contact is the subject of this invention, it is not necessary to describe the operating mechanism for the blade or a series of blades of a gang switch. Each blade is usually mounted on an ordinary pivoted insulator (not shown) adapted to be manufactured by a hand lever. Neither is it necessary to disclose the ordinary flexible conductor or cable adapted to be connected to a flange 31 on the jointed end of the tip and

threaded through the bars 22 to carry the current between the knee joint and the line conductor beyond the pivoted insulator.

From the foregoing description, it will be seen that the improved switch is relatively simple; that there are only a few parts which require machine operations; that the size and weight of the parts are considerably less than the size and weight of the parts of the ordinary switches having the same capacity; and that the cost of manufacture is considerably reduced.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. In an electric switch of the character described, a pair of spring jaws having associated transverse fulcrum means; and a toggle-jointed switch blade having a contact tip with an integral extension arranged to engage behind the fulcrum means upon opening and closing movement of the blade so that the contact elements are engaged and disengaged by a lever action.

2. In a knife switch of the class described, a jointed blade; a pair of spring jaws to receive the blade and arranged to provide a high-pressure contact; lever means on the blade; and a transverse fulcrum on the jaws coacting with the lever means automatically to increase the closing force applied to the blade during the final stages of its closing movement.

3. In a knife switch of the class described, a jointed blade; a pair of jaws to receive the blade and arranged to provide a high-pressure contact; fulcrum members associated with the jaws; and a lever member on the blade arranged to engage one fulcrum member when the contact portion of the blade approaches its closed position so as to increase the closing pressure and to engage another fulcrum member as the blade begins to open so as to increase the opening force until the blade clears the jaws.

4. In an electric switch of the class described, a pair of high-pressure contact jaws; a toggle-jointed blade; a lever projection on the end of the blade; and a transverse fulcrum member supported by the jaws in the path of movement of the blade and so arranged that the lever projection engages behind it after the blade tip strikes the jaws and the knee joint of the toggle begins to straighten whereby to increase the final closing pressure applied to the blade.

5. In an electric switch of the class described, a pair of high-pressure contact jaws; a toggle-jointed blade; a lever projection on the end of the blade; a pair of parallel arms

- projecting rearwardly from the jaws; and a transverse fulcrum pin carried by the arms and arranged in the path of movement of the lever projection so that the lever engages behind the pin as the blade tip approaches closed position and the knee joint of the toggle begins to straighten due to the resistance offered by the jaws whereby the final closing pressure is greatly increased.
- 5 6. In an electric switch of the class described, a pair of high-pressure contact jaws; a toggle-jointed blade having a spring normally to break the knee joint; arms projecting from the jaws; a fulcrum pin mounted in the arms across the path of the blade; a combined blade abutment and fulcrum member adjacent to the bottom of the jaws; a lever projection on the end of the blade arranged to engage said fulcrum pin during the final 10 closing movement of the blade and to engage the fulcrum member when the blade is being initially opened.
- 15 7. In an electric switch of the class described; a jaw supporting bracket; a spring plate secured between its ends on the bracket; jaws mounted on the opposite end portions of the plate; a toggle jointed blade presenting rounded contact portions to have high-pressure line contact with the jaw faces; 20 a fulcrum flange projecting from one of the jaws; a fulcrum pin carried by the jaws; and a lever projection on the end of the blade arranged to engage said fulcrum pin upon final closing movement of said fulcrum flange 25 upon initial opening movement.
- 30 8. In a horizontal knife switch of the class described, a jaw-supporting bracket; a horizontal spring plate secured between its ends to the bracket; a pair of jaws secured to the 35 end portions of said spring plate; a flange on one end of the jaws providing a limiting stop for the blade and extending rearwardly from the jaws in the path of movement of the blade to provide a fulcrum; rearwardly projecting 40 parallel arms on the jaws; a fulcrum pin on the ends of said parallel arms; a toggle-jointed blade having a contact portion of substantially elliptical cross section; a spring 45 connected normally to break the knee joint of the blade; stop means to limit the angular movement of the jointed legs; and a lever projection on the end of the blade arranged to be projected behind said fulcrum pin after the contact portion of the blade strikes the 50 jaws and the knee joint begins to straighten whereby the blade is finally closed by a powerful lever action, said lever also being arranged to engage the rearward extension of 55 said flange when the blade is initially opened 60 and the knee joint begins to break so that the blade is released by a powerful lever action.

In testimony, that I claim the foregoing as my own, I have hereto affixed my signature.

TOMLINSON F. JOHNSON.
